UNITED STATES PATENT OFFICE

2,552,740

BRUSH PACKAGING

Lawrence R. Schumann, Boston, Mass.

Application May 8, 1947, Serial No. 746,777

4 Claims. (Cl. 206—45.33)

1

This invention relates to a package for the bristles of a brush and more particularly to a transparent case to be used with a brush for display purposes.

When brushes are displayed for sale or other purposes, it is necessary to cover the bristles to protect them from dust and dirt. At the same time, it is desirable to have the bristles visible so that prospective purchasers or others may see them without removing the covers. Certain prior brush containers have been constructed of transparent material, but these containers are made of paper or other thin material which is not rigid. Therefore these containers do not prevent the bristles from becoming crooked and twisted if the brush is inspected, especially if it is rested on the ends of the bristles during this inspection. Also, wrappers made of such pliable materials are without form and therefore fit closely to the bristles and tend to fall in at the tip of the wrapper in such a manner as to compress the ends of the bristles. This action has a harmful effect on the shape of the brush.

One object of this invention is to provide a transparent brush package which supports and maintains the bristles in proper shape.

Another object is to provide a brush package of simple and inexpensive construction which shields the bristles from dust and dirt, protects the bristles from twisting and deformation and yet is transparent so as to display the brush effectively.

Other objects will appear from the following description, read in connection with the accompanying drawings, in which:

Figure 1 is a perspective view of one form of a brush package embodying the present invention.

Figure 2 is a vertical sectional view of the package shown in perspective in Figure 1, as seen from one side, and showing the bristles and ferrule of a brush in place in the package.

Figure 3 is a vertical sectional view of another embodiment of this invention.

Figure 4 is a sectional view on the line 4—4 of Figure 3.

Figure 5 is a vertical sectional view of a third form of the invention.

Figure 6 is a sectional view on the line 6—6 of Figure 5.

Like reference characters refer to like parts throughout the several figures of the drawings.

In the drawings, the handle of a brush which may be of oval, oblong or flat shape is indicated by the numeral 1. The handle 1 is broken off in the drawings at the shoulder, to which is secured

2

a ferrule or ring 2 for holding in place the bristles 3. These bristles 3 may be of any suitable type of hair or of any other suitable material and may be secured to the brush by any appropriate means, as by vulcanizing their ends in rubber.

In the embodiment of the invention illustrated in Figures 1 and 2, the brush package itself comprises a frame 4, which is preferably a strip or sheet of cardboard, pasteboard or other appropriate inexpensive, stiff material of sufficient width to extend across the thickness of the brush. Frame 4 constitutes the lining or skeleton of the package and is bent in two right angles to form a U-shaped or channel-shaped reinforcing member in three sections enclosing snugly two sides and the bottom end of the bristle bundle or cluster 3.

About the three sections and the open sides of reinforcing strip 4 is wrapped a sheet of transparent material 5, such as cellophane or other transparent cellulose or plastic, waxed paper or other desired material. This transparent material 5 may be folded about framework 4 so as to hold the framework in to provide a snug fitting against the ribs 6 of the ferrule. The envelope formed by material 5 is open at its upper end to receive the ferrule 2 of the brush. The folded edges 7 of material 5 may be secured together by any suitable means, such as heat welding, cementing, gluing or other appropriate method. The material 5 is held in a distended position by the tension of strip 4 at its bent corners, where the cardboard or other material of the strip tends to open the bent corners outwardly to flatten the strip.

The form of the invention shown in Figures 3 and 4 includes a lining or sheet 8 of cardboard or other stiff material like that of frame 4 of the form shown in Figures 1 and 2. The lining or frame 8 is channel-shaped or U-shaped so as to enclose three sides of ferrule 2 and bristle bundle 3 of a brush. The lining 8 is enclosed an all sides and at its bottom end, but not at the top end, which is open to receive the ferrule 2 of the brush, by transparent material 5. The latter compresses framework 8 against ribs 6 of ferrule 2 to hold the package to the brush. The material 5 is folded and the edges are secured together at 7 by cementing or by other means.

In Figures 5 and 6 is illustrated a third embodiment of the invention wherein a frame or sheet 9 of cardboard or similar material is bent once to form a right-angled or L-shaped supporting lining. Frame 9 may extend either partially or all the way across one side of ferrule 2 and bristle bundle 3 of the brush and also contacts another

side thereof. As in the other embodiments of the invention, frame 9 and the brush contained therein are enveloped on all four sides and on the bottom end by transparent material 5, which holds itself and frame 9 against ribs 6 of the ferrule by being folded at 7, where the edges of material 5 are glued, cemented or otherwise secured together. As in the other embodiments, the casting formed by material 5 is open at its upper end to receive the ferrule 2 of the brush.

In use, a brush is inserted in the package when it is desired to place the brush on display or for other reasons it is desired to have the brush visible while at the same time providing protection for the bristles from dust and dirt. The package is maintained in position on the brush by frictional contact of lining 4, 8 or 9 with ribs or ridges 6 of ferrule 2 of the brush. The package, because of the support provided by the lining, protects the bristles from becoming twisted, mashed or otherwise deformed and the transparent cover 5 protects the bristles from dust, dirt, moisture or other matter which might collect on the bristles and cause either physical deterioration to them or make their appearance unsightly.

The package is of simple construction, is easily manufactured and employs only a small amount of materials, so that it is inexpensive.

I claim:

1. A package comprising a paint brush having a handle extending from a shoulder, bristles extending from the end of the shoulder opposite the handle, a cover for the bristles, said cover comprising a U-shaped blank of stiff material constructed and arranged to lie against three surfaces of the mass of bristles to provide support for the bristles, said blank engaging side walls of the shoulder of the paint brush and extending to the ends of the bristles, and a flexible transparent sheet overlying the U-shaped blank and enclosing the bristles, said sheet being sealed along its edges to exclude dirt from the bristles and hold the blank in place against the shoulder of the brush whereby the bristles are displayed on two sides and supported by the strip on three sides.

2. A package comprising a paint brush having a handle extending from a shoulder, bristles extending from the end of the shoulder opposite the handle, a blank of cardboard or the like having a side panel extending at substantially right angles from each end of an end panel, said blank having a width substantially equal to the thickness of the mass of bristles, said blank positioned with the side panels against the opposite sides of the shoulder and the end panel extending between the end panels adjacent the ends of the bristles to form a frame around the bristles, and a flexible sheet of transparent material wrapped over the blank

to hold the blank in place against the shoulder and the sides and end of the bristles to form a substantially rigid package extending to the ends of the bristles, said sheet being sealed to exclude dirt from the bristles whereby the bristles are supported on the sides and the end and are displayed through the transparent wrapping on two faces.

3. A package comprising a paint brush having a handle extending from one end and bristles from the other end of a shoulder, a blank of cardboard or the like having a central panel and side panels extending substantially at right angles along each side of the central panel, said blank positioned with the panels engaging the shoulder of the brush and extending to the ends of the bristles, a flexible transparent sheet wrapped around the blank to hold the blank in place against the shoulder of the brush and each of the panels against a side of the bristles whereby the bristles are supported on three sides by the blank and displayed on the fourth side and at the end by the transparent sheet, said blank and transparent sheet terminating at the shoulder to expose the handle of the brush.

4. A package comprising a paint brush having a handle extending from one end and bristles from the other end of a shoulder, a blank of cardboard or the like engaging the outer surface of the shoulder and extending along the bristles of the brush to the end of the bristles, a flexible transparent sheet wrapped around the blank and the bristles to hold the blank in place against the shoulder of the brush and provide a substantially rigid package from the end of the handle to the end of the bristles whereby the bristles are supported by the blank and displayed through the transparent sheet, said sheet being sealed to exclude dirt from the bristles, said blank and sheet terminating at the shoulder of the brush to expose the handle of the brush.
